AUTOMATIC DRAFT CONTROL

William B. Stephenson and James S. Lee,
Fond du Lac, Wis.

Application August 17, 1949, Serial No. 110,804

20 Claims. (Cl. 236—45)

1

The present invention relates generally to improvements in draft controls, and more particularly to such controls for automatically admitting air to a furnace or boiler stack or breeching to regulate the draft intensity and prevent an excess flow of air through the combustion chamber of the furnace or boiler.

A general object of the invention is to provide a novel draft control which is operable to maintain a substantially constant predetermined negative pressure in the combustion chamber under all atmospheric conditions, and to effectively close the air intake opening in the furnace stack in the event of sudden positive pressure increase in the combustion chamber.

A further object of the invention resides in the provision of a draft control which is especially effective in angular installations and in connection with mobile boiler installations, such for example as in locomotives and steamships which are subject to roll and pitch.

A further object of the invention is to provide a novel draft control permitting of installation alternatively in upright or inverted positions according to space restrictions.

The objects of the invention thus generally set forth together with other objects and ancillary advantages are obtained by the constructions and arrangements shown by way of illustration in the accompanying drawings in which:

Figure 1 is a perspective view of an automatic draft control embodying the features of the present invention.

Fig. 2 is a front elevation on an enlarged scale of the draft control shown in Fig. 1.

Fig. 3 is a fragmentary vertical section taken along the line 3—3 in Fig. 2.

Fig. 4 is a fragmentary horizontal sectional view taken substantially in the plane of line 4—4 in Fig. 3.

Fig. 5 is a fragmentary horizontal sectional view taken substantially in the plane of the line 5—5 in Fig. 3.

Fig. 6 is a fragmentary rear perspective view of a lower corner of the swinging frame and damper plate of the draft control illustrated in the preceding figures.

Fig. 7 is a fragmentary front elevation of another form of the automatic draft control embodying features of the present invention.

Fig. 8 is a fragmentary vertical section through the form of the invention shown in Fig. 7.

Fig. 9 is a fragmentary vertical section taken substantially in the plane of line 9—9 in Fig. 8.

2

Fig. 10 is a fragmentary front elevation of still another form of the invention.

Fig. 11 is a side elevation, partly in section, of the form of the invention illustrated in Fig. 10.

5 While the invention is susceptible of various modifications and alternative constructions, there are shown in the drawings and will herein be described in detail the preferred embodiments, but it is to be understood that it is not intended thereby to limit the invention to the specific forms disclosed, but it is intended to cover all modifications and alternative constructions falling within the spirit and scope of the invention as expressed in the appended claims.

15 Referring more particularly to the drawings, the novel draft control includes a duct 10 adapted to be attached to and extend laterally from a stack or flue 12 leading from a furnace or boiler (not shown), and as illustrated, is placed endwise over an opening 18 in a vertical wall thereof.

In its preferred form, the duct 10 is of substantially square cross section having at one end an outwardly extending flange 14 formed of angle iron rigid therewith for purposes of securing 20 the same to the wall of the stack 12. The opposite end of the duct 10 is bordered by an inwardly extending flange 16 defining an air inlet opening 18.

25 In accordance with the invention, a closure device, generally indicated by the reference numeral 20, is provided for the opening 18, and it includes means responsive to pressure changes in the stack to open and close, and when open to admit air into the stack from outside the furnace

30 and thereby effect stabilization of the draft at a predetermined value, selectable as desired, together with supporting means therefor effective to permit proper operation regardless of the position of the duct, whether in angularly disposed 35 installations or in systems which are themselves subject to movement.

30 In carrying out the invention, the closure device comprises a pivoted supporting frame 22 which defines a secondary air inlet opening 22a

45 and which is adapted to maintain a vertical position, and a damper plate 24 pivotally supported on the frame 22, together with counterbalancing means, generally designated 26, for the damper plate effective to maintain the same normally in engagement with the frame 22 to close the frame opening 22a. Provision is also made to minimize leakage of air into the duct 10 about the frame 22.

50 In the first of the exemplary embodiments of the invention, as illustrated in Figs. 1 to 6, inclusive, the frame 22 is made of angle stock and

shaped to conform substantially to the interior of the duct 10. Thus, it is of rectangular outline and of a size slightly smaller than that of the interior of the duct.

So that the frame 22 will be maintained in a vertical position perpendicular to the side walls of the duct 10 under conditions of angular duct mounting or plant movement, it is pivoted at its top edge for free swinging movement within the duct. Thus, it is supported on a transversely extending rod or shaft 30, the ends of which are journalled in anti-friction bearings 32 which are preferably of the ball bearing type. The bearings 32 are, in turn, supported in brackets 34 which are secured to the side walls of the duct 10, intermediate mounting plates 35 which are rigid with the duct walls being utilized in the present embodiment to provide increased strength. To insure exact transverse mounting of the shaft 30 whereby free swinging of the frame within the duct obtains, each bracket 34 preferably is pivotally secured to its respective mounting plate 35 as by a bolt 36, and is provided with an adjusting screw 38, operating through a tapped hole in a lug 39 rigid with the plate, whereby to permit individual adjustment of the respective brackets, and hence the positions of the shaft supporting bearings 32.

If desired, further to insure free swinging of the frame 22 under conditions of horizontal tilting, the frame may be equipped with side thrust bearings 40 which, as shown in Figs. 5 and 6, are mounted at each of the lower corners of the frame in engagement with the side walls of the duct 10 and disposed for rotation about a vertical axis.

Should the weight of the frame itself be insufficient to insure its maintenance in vertical position, the frame may be equipped with a weight 42 (Figs. 3 and 5), which, as shown, is attached centrally of the lower transverse member thereof.

To minimize air leakage into the duct 10 beneath the frame 22, especially as the frame swings from its position illustrated in Fig. 3 in either direction within the duct 10, there is provided in cooperative association with the free swinging edge of the frame an apron 41, the upper surface of which is curved about the axis of the shaft 30. The apron 41 is attached to the bottom of the duct 10 and extends from the outer end thereof, overlapping the flange 16, inwardly into the duct to a point slightly beyond the normally expected range of swing of the frame 22. The inner end of the apron 41 is bent downwardly, and is flanged where it is welded or otherwise rigidly secured to the bottom wall of the duct 10.

In the present embodiment of the invention, the damper plate 24 is pivotally supported adjacent its lower edge and, when in closed position, bears against the inside marginal edge of the swinging frame 22, a strip 43 of cushioning material, such as felt, being disposed between the engageable portions of the plate and frame for shock-deadening purposes. Preferably, the strip 43 is cemented to the inner face of the transversely extending portions of the frame 22.

To provide a pivotal mounting for the damper plate 24, it is secured to a transverse rod or shaft 44 in any suitable manner, the opposite ends of which are journalled in anti-friction bearings 46. These bearings are also preferably of the ball bearing type, and have their outer races received in brackets 48 welded or otherwise rigidly secured in the lower corners of the frame 22.

The counterbalancing means 26 which is pro-

vided to oppose the action of the draft on the damper plate 24, includes counterweights 50 which are adjustable in position both horizontally and vertically to permit change of location of the center of gravity of the damper plate and counterbalancing system with respect to the pivotal axis, so that the definite force acting in opposition to the suction on the plate due to the stack draft is maintained for a particular counterweight arrangement. Accordingly, a predetermined draft intensity is maintained through the furnace or boiler. The damper plate, moving in response to the difference between the draft force and the counterbalancing force, is thus effective to compensate for draft fluctuations by varying the effective inlet area of the frame opening 22a.

In the present instance, the counterweights 50 are supported at the ends of a horizontal crossbar 52, the latter being fastened intermediate its ends to a depending supporting arm 54 which is preferably channel-shaped. The upper end of the arm 54 is pivotally connected to the damper plate 24, which as illustrated is accomplished through the use of a pair of brackets 55 and 56 and a pivot pin 57. The bracket 55 is of elongated U-shape and is attached in vertical position centrally of the plate 24. The bracket 56 is also of U-shape, and has its bight portion fixed adjacent the upper end of the bracket 55 so that its arms extend outwardly. These arms and the upper end of the counterweight supporting arm 54 are appropriately apertured to receive the pivot pin 57 which is retained in position in any suitable manner, as by cotter pins 58. This mounting permits free forward and backward swinging of the arm about a transverse horizontal axis and effectively prevents any tendency thereof to rotate or twist about vertical or longitudinal axes.

To permit free fore and aft movement of the depending arm 54 and the frame weight 42, both of which are adapted to extend below the duct 19, the bottom wall of the duct and the apron 41 are provided with registering longitudinally extending slots 10a and 41a, respectively (Fig. 5).

Each of the counterweights 50 comprises a closed upwardly curved tube 60 of substantially quadrantal form having a heavy metal ball 62 disposed therein which is adapted to move along the tube under the influence of gravity upon movement of the damper plate and counterbalancing system. To enhance the sensitivity of the counterbalancing means, the balls 62 may be floated on a small quantity of mercury as indicated at 64. Bridging the end of the tubes 60 is a bar 66 which is slidably received in a guide 68 rigid with the ends of the crossbar 52. Thus the counterweights 50 may be shifted forwardly or rearwardly with respect to the depending arm 54 to produce a corresponding shifting of the center of gravity of the damper plate and counterbalancing system. Each guide 68 is equipped with a set screw 68a by means of which the bar 66 may be clamped within the guide so as to maintain the desired position of the counterweight.

Provision is made for raising and lowering the counterweights 50 so as to vertically adjust the center of gravity of the system with respect to the pivotal axis. To this end, the arm 54 is provided with a series of spaced apertures 69 for the reception of a bolt 70 carried intermediate the ends of the crossbar 52.

As an additional means of adjustment there is provided a thumb screw 72 supported on the de-

pendent arm 54 and engageable with the bracket 55, which is rigid with the damper plate 24. The thumb screw 72 is operable to vary the angular relationship between the depending arm 54 and the plane of the damper plate. When such angular relationship is determined, maintenance thereof is assured by means of lock nuts 74 disposed on opposite sides of the depending arm and engageable therewith to lock the screw in the desired position.

It will be evident that the damper plate 24 and the counterbalancing means are constrained to move in synchronism. As the damper plate 24 swings inwardly in response to an increase in the draft above a certain predetermined value, thus effectively increasing the air inlet area, the counterweights 50 are swung in a clockwise direction as viewed in Fig. 3, upwardly and outwardly. Conversely, as the draft decreases, the damper plate and the counterweights swing in the reverse direction. Hence, the control tends to seek a position of balance and thus serves to compensate fluctuations in the draft by controlling the inflow of air into the stack from outside the furnace or boiler.

Initial opening movement of the damper plate 24 takes place immediately upon the draft intensity exceeding the predetermined desired value, i. e. the counterforce exerted by the counterbalancing means as selected and adjusted, and air enters the duct 10 at a considerable velocity; hence, the plate is sensitive to even small pressure fluctuations. However, as the plate is caused to swing progressively toward its maximum open position, it tends to become less sensitive to changes in the draft, that is to say, its operation becomes lazy. While the closing force exerted by the counterbalancing means increases as the plate 24 moves toward fully open position, the balls 62 and the mercury 64 move along the tubes 60 to reduce the rate of increase, thus rendering the plate more sensitively and accurately responsive when open a substantial distance, thereby overcoming any lazy tendencies.

The curvature of the weight-supporting tubes 60 controls the action of the balls 62 and the mercury pool 64. The greater the radius of such tubes, the more rapid will be the action of the balls and the mercury, and the more apt will be the noisy banging of the balls against the tube ends. Decreasing this radius tends to slow the action of the balls and decrease the sensitivity of their response. It has been found that a radius of curvature of approximately 12 inches is the most practical for general application.

With the adjustments hereinbefore described for the counterbalancing means, the control is adaptable for an almost infinite number of different installations and for different operating conditions. It will be apparent that each of the counterweights 50 may be adjusted on the arm 54 transversely of the shaft 30. If the two counterweights are both adjusted to their outermost positions, a heavy closing action will be obtained. If the counterweights are both adjusted to their innermost positions, a light closing force is exerted which is sufficient barely to hold the plate 24 against the swinging frame 22. Any desired intermediate adjustment within the wide range defined by these limits may be attained.

Turning now to Figs. 7 to 9, inclusive, of the drawings, the modified form of the invention there shown may be termed an inverted control, as compared to the form just described. For the sake of brevity, similar elements are denoted

by the primes of like reference numerals. This draft control as before includes a duct 10' rigidly secured over an opening 12a' in the vertical wall of a stack or flue 12', and having an angularly disposed forward end 16' just like that in the first embodiment described. In this embodiment, however, the damper plate 24' of the device is pivoted at its upper edge and on the same axis as is the swinging frame 22' and the counterbalancing means for the damper plate extends oppositely from that in the embodiment hereinbefore described. This form of the invention, then, may be termed an inverted control, as compared to the first form described.

10 To pivotally support both the swinging frame 22' and the damper plate 24' on a common axis, a single transversely disposed rod or shaft 30' is utilized. To support the damper plate 24' for pivotal movement with respect to the swinging frame 22', the latter is provided with apertured supporting members or brackets 80 rigid therewith for the reception of additional anti-friction bearing elements 82. The damper plate 24' is rigidly secured to the shaft 30' and the latter, 20 while extending through openings in the sides of the swinging frame, is free to rotate therein.

25 The counterbalancing means 26' in this embodiment includes the same elements as previously set forth for the first embodiment described; however, their action, due to the inverted relationship of the damper plate and swinging frame, is the reverse of that previously set forth. This necessitates only a simple rearrangement of elements, and a single structural modification. 30 It will be noted that most of the weight of the counterbalancing means is disposed above the plane of the pivotal axis of the system including the damper plate and counterbalancing means. Thus the adjusting screw 72' is rotatably anchored adjacent the upper end of the damper plate bracket 55' to prevent the counterweight supporting arm 54' from swinging in a counter-clockwise direction, as shown, about the pivotal axis and out of operative relation with respect to the damper plate.

40 In the other modified form of the invention as illustrated in Figs. 10 and 11 wherein similar elements are denoted by the double primes of like reference numerals, the duct 10'' and the elements of the control rigid therewith, including the rear marginal supporting flange 14'', the flange 16'' defining the air inlet opening 18'', and the apron 41'', are mounted in a position inverted with respect to those shown in the preceding em- 45 bodiments. The damper plate 24'' and the counterbalancing means 26'' therefor are disposed and operate in the same manner as described for the first form of the invention, namely, that illustrated in Figs. 1 to 6, inclusive. In

50 this form, however, the swinging frame 22'' is adapted for movement about a transverse axis 30'' which is disposed adjacent the bottom edge instead of the top edge of the frame. The pivotal mountings of both the swinging frame and the damper plate are the same as described for the second form of the invention, namely, that illus- 55 trated in Figs. 7 to 9, inclusive.

60 Since the frame 22'' extends upwardly from its pivotal axis, additional counterbalancing means 70 for it is provided. Thus, adjacent each of its side edges, the frame 22'' has attached thereto a pair of depending arms 86 on which are supported relatively heavy counterweights 88. If desired, these weights may be adjustably sup- 65 ported on the arms 86 by means of slides 89.

through which the arms are passed. To permit clearance of the bottom wall of the duct 10", each of the arms 86 has an intermediate U-shaped portion 86a formed therein near its upper end. As shown, however, the upper and lower extremities of the arms are disposed parallel to the plane of the side members of the swinging frame 22". The counterbalancing weights 88, of which there may be any suitable number, may be alternately arranged to front and back thereof for proper adjustment of the center of gravity of this counterbalancing means to assure maintenance of the frame 22" in a vertical position.

From the foregoing it can be seen that only minor changes of structure and simple rearrangement of elements are necessary to permit installation of draft control devices constructed in accordance with the present invention in almost any furnace or boiler system that might be encountered. The illustrative embodiments demonstrate that rotation of the damper plate and the swinging frame may be attained about the same or about separate axes and disposed at the top or at the bottom of the duct. As between the second and third exemplary forms of the invention illustrated, the change necessary is the addition of the counterweights 88 for the swinging frame so that the same is maintained in vertical position. The counterbalancing means for the damper plates renders them self-closing. The suction of the draft tends to move the plate into open position against the action of the counterbalancing means and the latter is accurately adjustable over a wide and finely graduated range, fineness of adjustment being attained by the use of the thumb screws 72, 72' or 72" which alter the angular relation between the counterweight supporting arms and the damper plate. In the inverted control, when the arm 54' is adjusted rearwardly of the plane of the plate, it operates to move the damper plate toward closed position. In the normally operating controls, the forms illustrated in Figs. 1 to 6 and in Figs. 10 and 11, this action is reversed so that if the arm 54 or 54" and the counterweights 50 or 50" attached thereto are angularly adjusted outwardly from the plane of the plate, the action of the counterbalancing means will be to resist a substantial draft before permitting opening of the damper plate in response to draft suction.

The farther away from the pivotal axis of the damper plate the counterweights are moved along the arm 54, the greater will be the leverage and consequently the effect on the action of the damper plate.

By adjusting the counterweights, jointly or individually backward or forward in relation to the crossbar, a fairly critical counterbalancing adjustment can be made. Positioning of the weights at opposite ends of their supporting bars and relative to the crossbar effects great sensitivity of the damper plate at or near its closed position, making it responsive to very slight barometric changes and very gentle in its action. With the counterweights side by side and at their rearmost positions in relation to the crossbar, the damper plate will just barely close against the swinging frame. Conversely, with the weights side by side and at their foremost positions in relation to the crossbar, the closing action on the damper plate 24 is increased to maximum and the plate is held against the swinging frame until a considerable suctional force of draft obtains. In the inverted control, these adjustments will have the reverse effect.

The wide range of adjustment of the counterbalancing means, together with the available fineness thereof, is of great importance due to the many prevailing sizes and heights of chimneys, the widely varying characteristics of fuels and heat generating plants together with the differing requirements of specific installations as to space limitations and as to special purposes.

We claim as our invention:

1. An automatic draft control comprising, in combination, a duct of rectangular cross section adapted to be secured over an opening in a stack and open at its free end, a rectangular frame fitting closely within the duct adjacent the open end thereof and having an inner marginal flange defining a rectangular air inlet opening, means for pivotally supporting said frame for free swinging movement so that the frame will maintain a vertical position regardless of angular disposition of the duct, a damper plate pivotally supported at one edge thereof on said frame and normally engaging the inside of said flange to close said opening, said plate being swingable about a horizontal axis inwardly from said opening in response to a draft increase in said stack, and counterbalancing means operatively connected with said plate and tending to urge the same into closed position.
2. An automatic draft control comprising, in combination, a duct adapted to be secured over an opening in a stack and having an air inlet opening in its outer end, a frame pivotally supported adjacent its top edge and adjacent the top wall of the duct so as to maintain a vertical position transversely of the duct regardless of angular disposition of the latter, and a damper plate pivoted on said frame and counterbalanced to normally bear thereagainst so that said frame and plate are normally effective to close off said air inlet opening, said counterbalanced damper plate being movable into an open position in response to a draft increase within the stack to admit air directly into the stack whereby to maintain a substantially constant draft.
3. An automatic draft control, comprising, in combination, a duct adapted to be secured over an opening in a stack, a frame having an air inlet opening therein pivotally supported adjacent its lower edge and adjacent the bottom wall of the duct, counterbalancing means for said frame effective to maintain the frame in a vertical position transversely of the duct regardless of angular disposition of the latter, and a damper plate pivoted on said frame and counterbalanced to normally bear thereagainst to normally close said air inlet opening, said damper plate being movable into an open position in response to a draft increase within the stack to admit air directly into the same.
4. An automatic draft control comprising, in combination, a duct having an open outer end, a frame having an air inlet opening pivotally supported at its lower edge within the duct and adjacent the open end thereof, counterbalancing means operative to maintain said frame in a vertical position transversely of the duct, and a damper plate pivoted on said frame and counterbalanced to normally bear thereagainst to close off said air inlet opening, said damper plate being movable into an open position in response to a draft increase within the stack to admit air directly into the same, the counterbalancing means for said frame including an arm fixed at one end to said frame and formed to extend through the open end of the duct and clear the

bottom wall thereof and to extend substantially below the pivotal axis of said frame, and a weight secured adjacent the free end of said arm.

5. An automatic draft control comprising, in combination, a duct, a frame mounted in said duct and supported for free swinging movement about a horizontal axis so as to maintain a vertical position and having an air inlet opening therein, a damper plate pivotally mounted on said frame on a horizontal axis disposed adjacent the bottom of said frame for inward movement with respect to both the frame and duct to control the effective area of said opening, and counterbalancing means tending to maintain said plate in closed position.

6. An automatic draft control comprising, in combination, a duct, a frame mounted in said duct and supported for free swinging movement about a horizontal axis so as to maintain a vertical position and having an air inlet opening therein, a damper plate pivotally mounted in said frame on a horizontal axis disposed adjacent the top of said frame for inward movement to control the effective area of said opening, and counterbalancing means tending to maintain said plate in closed position.

7. An automatic draft control comprising, in combination, a duct, a frame mounted in said duct and supported for free swinging movement about a horizontal axis adjacent one edge thereof so as to maintain a vertical position transversely of the duct and having an inlet opening therein, a damper plate pivotally mounted in said frame on a horizontal axis adjacent the edge of the frame opposite its pivotal axis to control the effective area of said opening, and counterbalancing means tending to maintain said plate in closed position.

8. An automatic draft control comprising, in combination, a duct, a frame mounted in said duct and supported for free swinging movement about a horizontal axis disposed adjacent one edge thereof so as to maintain a vertical position transversely of the duct and having an air inlet opening therein, a damper plate pivotally mounted in said frame on the same horizontal axis as said frame but being swingable thereon independently of the frame to control the effective area of said opening, and counterbalancing means tending to maintain said plate in closed position.

9. An automatic draft control comprising, in combination, a duct adapted to be secured over an opening in a stack, a frame transversely disposed in said duct and pivotally mounted at one end thereof for free swinging movement to maintain a vertical position and having an air inlet opening, and means interposed between the free end of the frame and the wall of the duct adjacent thereto effective to minimize leakage of air therebetween, a damper plate pivotally mounted on said frame and responsive to draft fluctuations to control the effective area of said air inlet opening, and counterbalancing means for said damper plate tending to maintain the same in closed position.

10. An automatic draft control comprising, in combination, a duct, a frame transversely disposed in said duct and pivotally mounted at one end thereof for free swinging movement to maintain a vertical position and having an air inlet opening, an apron rigid with the wall of the duct adjacent the free end of the frame and having the surface thereof adjacent said free frame end formed to the arc traversed by the free frame

end whereby leakage of air into the duct is minimized, a damper plate pivotally mounted on said frame and responsive to draft fluctuations to control the effective area of said air inlet opening.

11. An automatic draft control comprising, in combination, an open-ended duct adapted to be secured over an opening in a stack, a frame transversely disposed in said duct and pivotally mounted for free swinging movement so as to maintain a vertical position, said frame having an inner marginal flange defining an air inlet opening, a damper plate pivotally mounted on said frame and responsive to draft fluctuations to control the effective area of said air inlet opening, and counterbalancing means for said damper plate tending to maintain the same in closed position.

12. An automatic draft control comprising, in combination, a duct, a frame fitting within said duct and having an air inlet opening, means for pivotally supporting said frame for free swinging movement about a generally horizontal axis extending transversely thereof, a damper plate mounted in said frame for swinging adjustment about a generally horizontal axis for controlling the effective area of said opening, and counterweight means operatively connected to said plate, said counterweight means being adjustable to alter the center of gravity of the system including said damper plate and counterweight means with respect to the pivotal axis of said damper plate whereby to adjust the degree of draft intensity necessary to effect movement of said damper plate into an open position.

13. An automatic draft control comprising, in combination, a duct, a frame defining an air inlet opening and mounted for free swinging movement to maintain a vertical position, a damper plate disposed in operative relation to said opening, means on said frame supporting said plate for swinging movement about a horizontal axis extending transversely of said frame, and counterbalancing means operatively connected with said plate and adapted to move the same into closed position with respect to said opening, said counterbalancing means including an arm pivotally secured to said plate, a generally horizontal crossbar adjustably secured to said arm and having a guide member thereon, an upwardly curved tube, a guide bar rigid with said tube and slidably received in said guide member for adjustment transversely of said plate axis, and a weight freely movable in said tube in response to gravity.

14. An automatic draft control comprising, in combination, a frame pivotally supported for free swinging movement so as to maintain a vertical position and having an air inlet opening, a damper plate pivotally supported on said frame for rotation about a horizontal axis in operative relation to said opening, an arm pivotally secured at one end to said plate, a crossbar adjustably secured adjacent the free end of said arm for movement therealong and having a generally horizontal guide member adjacent each of its ends, and a pair of counterweights each including a guide bar slidably received in said guide members and adjustable therein transversely of said plate axis, an upwardly curved tube rigid with said guide bar and a weight freely movable in said tube in response to gravity.

15. An automatic draft control comprising, in combination, a frame pivotally supported for free swinging movement so as to maintain a vertical position and having an air inlet opening therein, a damper plate pivotally supported on said frame

for rotation about a horizontal axis in operative relation to said opening, an arm pivotally secured at one end to said plate, a crossbar adjustably secured adjacent the free end of said arm for vertical adjustment therealong and having a generally horizontal guide member adjacent each of its ends, a pair of counterweights each including a guide bar slidably received in one of said guide members to permit adjustment of its position transversely of said plate axis, an upwardly curved tube rigid with said guide bar and a weight freely movable in said tube in response to gravity, and means operatively associated with said arm and said plate effective to vary the angular relationship between the two.

16. An automatic draft control comprising, in combination, a duct, a frame disposed within said duct and defining an air inlet opening, means supporting said frame adjacent one side thereof for free swinging movement about an axis extending transversely of the duct, said means being adjustable to insure exact transverse disposition of said axis, a damper plate pivotally supported in said frame and controlling said opening and counterbalancing means operatively connected with said plate tending to urge the same into closed position.

17. An automatic draft control comprising, in combination, a duct having top, bottom and side walls, a shaft extending transversely of the duct, a frame supported adjacent one end thereof on said shaft and having an air inlet opening, anti-friction bearings journaled in said shaft to permit free swinging movement of it and said frame so that the latter maintains a vertical position, supporting brackets for said bearings adjustable in position to insure transverse disposition of the shaft and frame within said duct, side thrust bearings supported on said frame adjacent the free end thereof and engageable with the side walls of the duct to prevent dragging of the frame thereon, and a counterbalanced damper plate pivotally supported on said frame and engageable therewith to close said opening.

18. An automatic draft control comprising, in combination, a duct, a frame mounted in said duct and supported for free swinging movement about a horizontal axis adjacent one edge thereof so as to maintain a vertical position transversely

of the duct and having an air inlet opening therein, a shaft extending transversely of said frame, anti-friction bearings supported on said frame and journaling said shaft, a damper plate rigid with said shaft and operative to control the effective area of said frame opening, and counterbalancing means operatively connected with said plate tending to maintain the same in closed position.

19. An automatic draft control comprising, in combination, a duct, a shaft extending transversely of the duct, a frame supported on said shaft and having an air inlet opening therein, anti-friction bearings supported on said duct and on said frame and journaled in said shaft, a counterbalanced damper plate rigid with said shaft and disposed within said frame and operative to control the effective area of said opening, said bearings permitting free swinging movement of said frame so as to maintain a vertical position and movement of said damper plate independently of said frame.

20. An automatic draft control comprising, in combination, a frame pivotally supported for free swinging movement to maintain a vertical position and having an air inlet opening, a damper plate pivotally supported on said frame for movement about a horizontal axis and operative to control the effective area of said opening, and counterbalancing means operatively connected to said plate tending to maintain the same in closed position with respect to said opening, said counterbalancing means including a counterweight disposed on the opposite side of said axis from said plate, said counterweight including a quadrant tube, a weight and a quantity of mercury movable in said tube in response to gravity.
